JAMES L. COOK.
by Atty N. Dubois.

UNITED STATES PATENT OFFICE.

JAMES L. COOK, OF SPRINGFIELD, ILLINOIS.

VALVE.

SPECIFICATION forming part of Letters Patent No. 574,881, dated January 12, 1897.

Application filed February 7, 1896. Serial No. 578,415. (No model.)

To all whom it may concern:

Be it known that I, JAMES L. COOK, a citizen of the United States, residing at Springfield, in the county of Sangamon and State of Illinois, have invented certain new and useful Improvements in Valves, of which the following is such a full, clear, and exact description as will enable those skilled in the art to which it appertains to make and use my said invention.

The purposes of my invention are to provide suitable means of novel and improved form adapted to prevent the escape of steam, air, or liquids, from the body of the valve around the valve-stem without the use of packing such as is ordinarily used in valves; to provide in the valve-bonnet ball-bearings adapted to facilitate the turning of the stem and reduce the friction between the bearing-surfaces; to provide simple and improved means whereby the disk within the valve-bonnet may be retained on its seat regardless of the pressure of steam or liquid within the valve; to provide simple and effective means whereby the disk may be connected with the valve-stem; to provide hardened surfaces—such as hardened-steel plates, for example—on which the balls within the valve-bonnet press; to provide means connecting the screw-cap with the valve-stem, so that the screw-cap may turn with the stem, and in general to provide a valve having ball-bearings and having in the bonnet of the valve a disk which is always in place on its seat whether the valve is open or closed.

With these ends in view my invention consists in certain novel features of construction and combinations of parts shown in the annexed drawings and hereinafter particularly described and specifically claimed.

In the drawings, to which reference is hereby made, Figure 1 is a side elevation of the complete valve. Fig. 2 is a vertical longitudinal section on the axis of the valve. Fig. 3 is a detached perspective view of the stem, a part of the disk-plate and the nut being shown as broken away so as to show the threaded part of the stem on which the nut screws. Fig. 4 is an enlarged perspective view of the ring fitting on the valve-stem. Fig. 5 is an enlarged detached perspective view of one of the bearing-plates.

Similar letters of reference designate like parts in all of the views.

I have shown my improvements as applied to a radiator-valve; but they may obviously be applied to valves of other kinds without departing from the spirit of or sacrificing any of the advantages of my invention.

The valve-body A may be of any usual and suitable form and need not be particularly described.

The valve-bonnet A' has its lower end threaded and screws into the top of the valve-body, as clearly shown in the drawings. In the lower part of the valve-bonnet are internal and diametrically opposite channels a.

The main valve B in the valve-body A has integral arms b, the ends of which slide in the channels a and serve to guide the movement of the valve B.

On the inside of the valve-bonnet is an annular downwardly-extending valve-seat a', on which a disk on the valve-stem seats, as hereinafter set forth. The valve-bonnet has near its upper end a diaphragm a², pierced by a central hole a³, through which the valve-stem passes. The valve-stem D has at its central part an integral disk-plate d, accommodating a disk D', which may be of fiber, vulcanized rubber, composition metal, or any other suitable material. In practice the disk D' may be entirely dispensed with and the top of the disk-plate d may be ground to fit on the valve-seat a' in the valve-bonnet. The lower end of the valve-stem is threaded, as at d', to fit in the stem of the valve B, as clearly shown in Fig. 2. The valve-stem has near its center a screw-threaded part d², which receives a nut D², which serves to retain the disk D' in place on the disk-plate. On the upper part of the stem D is a screw-threaded part d³, on which the screw-cap E fits. The tightening of the screw-cap E presses the disk D' firmly on its seat a', so as to effectually prevent leakage. The screw-cap E surrounds and incloses the upper end of the valve-bonnet, so as to exclude dirt and grit from the cavity in the upper part of the valve-bonnet in which the balls turn. The stem D has in its upper part a longitudinal channel d⁴, in which a lug f on the ring F fits, so that the ring turns with the stem and is prevented from turning independently of the stem,

thereby obviating loosening of the screw-cap when the stem is turned. The hand-wheel H fits on the upper squared end d^5 of the valve-stem.

5 The bearing-plates G are preferably made of hardened steel, but other suitable material may be used. The bearing-plates inclose the valve-stem and fit loosely in the cavity in the upper part of the valve-bonnet above the dia-
10 phragm a^2 . Balls J, between the bearing-plates G, surround the valve-stem and fill the cavity in the upper end of the valve-body. These balls serve to diminish the friction be-
15 tween the bearing-surfaces when the screw-
cap is screwed down and permit the stem to be readily turned and obviate undue wear of the surfaces in contact.

I prefer to use two bearing-plates G and a ring F, provided with a lug, as shown in the
20 drawings. It is obvious, however, that a thicker bearing-plate, having a lug fitting in the channel d^4 , may be substituted for the ring F and the upper bearing-plate without departing from my invention.

25 In assembling the parts the disk D' is placed on the disk-plate and the nut D² is screwed down to hold it in place. The lower bearing-plate is then placed in the cavity in the upper end of the valve-bonnet. The
30 valve-stem is then passed upward through the central hole in the diaphragm a^2 , so that the disk D' will bear squarely on the seat a' . The balls J are then disposed around the valve-stem on top of the lower bearing-plate G. The upper bearing-plate is then placed
35 on the stem above the balls. The ring F is next placed on the stem above the upper bearing-plate. The screw-cap E is then screwed on the top of the ring F, and the
40 hand-wheel H is then placed on the squared upper end of the valve-stem.

It will be seen that by tightening the screw-
45 cap E the plates G will be held in contact with the balls J and the disk D' will be caused to make a close connection with the valve-seat a' .

By turning the hand-wheel H the stem G will be turned so as to raise or lower the valve B in an obvious manner.

It will also be seen that the turning of the
50 valve-stem does not in any way affect the seating of the disk D', but the disk is always firmly seated whether the valve B is raised or lowered, the pressure of steam or liquid within the valve serving to additionally re-
55 tain the disk in place on its seat. Increasing pressure of steam or liquid within the valve only causes the disk to rest more firmly on its seat, thereby effectually preventing any leakage which might otherwise result from wear
60 of the parts.

The screw-cap E screws firmly down on the ring F and turns with the valve-stem and is independent of the valve-bonnet, so as to obviate any displacement of the screw-cap by

reason of engagement of the screw-cap with 65 the periphery of the upper end of the valve-
bonnet.

I am aware that balls have heretofore been used to reduce the friction between the bearing parts of valves. I therefore do not claim 70 that feature broadly. I am also aware that a nut has been used on a valve-stem having an integral collar to keep said collar in contact with an annular ledge on the inside of the bonnet of a valve, but I am not aware of 75 the use prior to my invention of a nut on the valve-stem surrounding and inclosing the upper end of the valve-bonnet, so as to exclude dirt from the cavity of the valve-bonnet. Neither am I aware of the prior use of a de- 80 tachable disk on the valve-stem seating on a seat in the valve-bonnet and adjustable on said seat by means of a nut on the valve-stem.

The operation of the valve is obvious from 85 the description.

Having fully described my invention, what I claim as new, and desire to secure by Letters Patent, is—

1. In a valve, the combination of a valve-
body provided with a valve-seat, a valve-
bonnet provided with a diaphragm and connected with the valve-body, said valve-bonnet having an annular downwardly-extending valve-seat also having diametrically opposite channels, a valve adapted to rest on the seat 95 in the valve-body and having arms sliding in the channels in the valve-bonnet, a channeled valve-stem carrying a disk seating on the seat in the valve-bonnet, bearing-plates fitting in the valve-bonnet above its diaphragm, balls 100 interposed between said bearing-plates and surrounding the valve-stem, a ring inclosing the valve-stem and having a lug fitting in the channel thereof, and a screw-cap screwing on the valve-stem above said ring and surrounding and inclosing the upper end of the valve-
105 bonnet, as set forth.

2. A valve-stem D having a slot d^4 , a screw d' , screw-threaded parts d^2 and d^3 , an integral disk-plate d , and a retaining-nut D², in 110 combination with a disk fitting on said disk-plate, a valve-bonnet having an internal seat on which said disk seats also having a cavity in its upper part, balls in said cavity, a ring surrounding said stem above said balls and 115 having a lug fitting in the channel in said stem, a screw-cap screwing on said stem above said ring, a valve-body with which said valve-bonnet is connected, and a slide valve B operated by the screw d' , as set forth.

In witness whereof I have hereunto subscribed, at Springfield, Illinois, this 4th day of February, 1896.

JAMES L. COOK.
